(57) **CLAIM**

The ornamental design for an inhaler, as shown and described.

DESCRIPTION

FIG. 1 is a perspective view of an inhaler from above and one side with the mouthpiece cover in the closed position. FIG. 2 is a perspective view of the device from below and other side with the mouthpiece cover in the closed position. FIG. 3 is a front view of the device with the mouthpiece cover in the closed position.

FIG. 4 is a rear view of the device with the mouthpiece cover in the closed position.

FIG. 5 is a side view of the device with the mouthpiece cover in the closed position.

FIG. 6 is the other side view of the device with the mouthpiece cover in the closed position.

FIG. 7 is a top plan view of the device with the mouthpiece cover in the closed position.

FIG. 8 is a bottom plan view of the device with the mouthpiece cover in the closed position.

FIG. 9 is a perspective view of the device from above and one side with the mouthpiece cover in the open position.

FIG. 10 is a perspective view of the device from below and other side with the mouthpiece cover in the open position.

FIG. 11 is a front view of the device with the mouthpiece cover in the open position.

FIG. 12 is a rear view of the device with the mouthpiece cover in the open position.

FIG. 13 is a side view of the device with the mouthpiece cover in the open position.

FIG. 14 is the other side view of the device with the mouthpiece cover in the open position.

(Continued)

FIG. 15 is a top plan view of the device with the mouthpiece cover in the open position; and,

FIG. 16 is a bottom plan view of the device with the mouthpiece cover in the open position.

The broken lines in the drawings show portions of the inhaler that form no part of the claimed design.
